UNITED STATES PATENT OFFICE

103,676

DESIGN FOR A SCREW DRIVER

Thomas J. Fegley, Jenkintown, and George O. Leopold, Philadelphia, Pa., assignors to North Bro's Mfg Co., Philadelphia, Pa., a corporation of Pennsylvania

Application August 6, 1936, Serial No. 64,282

Term of patent 7 years

To all whom it may concern:

Be it known that we, Thomas J. Fegley and George O. Leopold, citizens of the United States, residing, respectively, in Jenkintown, Montgomery County, Pennsylvania, and Philadelphia, Philadelphia County, Pennsylvania, have invented a new, original, and ornamental Design for a Screw Driver, of which the following is a specification,

reference being had to the accompanying drawing, forming part thereof, in which the figure is a side elevation of the screw driver.

We claim:

The ornamental design for a screw driver, substantially as shown.

THOMAS J. FEGLEY.
GEORGE O. LEOPOLD.
